Design U.S. Appl. No. 29/629,299, "Design Application for Coated Abrasive Discs", filed Dec. 12, 2017.

(Continued)

Primary Examiner — Patricia A Palasik(74) *Attorney, Agent, or Firm* — Bradford B. Wright(57) **CLAIM**

The ornamental design for a coated abrasive disc, as shown and described.

DESCRIPTION

FIG. 1 is a perspective view of a coated abrasive disc showing the new design for a coated abrasive disc. As shown, the coated abrasive disc is oriented with the top surface shown uppermost on the disc;

FIG. 2 is an enlarged view of region 2 in FIG. 1;

FIG. 3 is a top view of the coated abrasive disc;

FIG. 4 is a left side view of the coated abrasive disc; and,

FIG. 5 is a front side view of the coated abrasive disc.
